[57] CLAIM

The ornamental design for a battery key chain light, as shown.

DESCRIPTION

FIGS. 1-4 are perspective views of a battery key chain light showing my new design, and showing its key chain ring in various positions, including a tucked away position (FIG. 3); FIG. 5 is a front elevational view thereof; FIG. 6 is a rear elevational view thereof, with the key chain ring shown in its tucked away position; FIG. 7 is a right side elevational view thereof, with the key chain ring shown in an extended position, the left side elevational view being a mirror image thereof; FIG. 8 is the bottom view thereof; and, FIG. 9 is the top view thereof.
